JULIUS BIDERMAN, OF NEW YORK, N. Y.

COMB.

1,425,937.

Specification of Letters Patent. Patented Aug. 15, 1922.

Application filed March 12, 1921. Serial No. 451,932.

To all whom it may concern:

Be it known that I, JULIUS BIDERMAN, a citizen of the United States, residing at New York city, in the county of Kings and State 5 of New York, have invented certain new and useful Improvements in Combs, fully described and represented in the following specification and the accompanying drawing, forming, a part of the same.

10 This invention relates to combs, and has for an object to provide a comb which will cleanse the hair through which it is passed. Other objects of the invention and uses of the new comb are hereinafter described.

15 In hair combs heretofore made, it has been customary to space the teeth a considerable distance apart and to avoid sharp angles in the spaces between the teeth. Such combs have little, if any, cleansing action upon the 20 hair.

According to the present invention the comb is constructed of a series of thin strips or laminæ arranged side by side and in contact with each other, and each having a 25 tapered or pointed portion forming a tooth of the comb. Each side of each strip is provided with a contact surface conforming to the adjacent contact surface of the succeeding strip, and with a slightly tapering 30 surface continuing from the contact surface and forming a side of one of the teeth of the comb. In a comb so constructed the spaces between the teeth taper off to a point so that strands of the hair through which 35 the comb is passed are drawn up into the point and closely engaged by adjacent teeth. In order to secure a thorough cleansing of the hair, I have found it most desirable to mount the strips so that the teeth and the 40 contact surfaces of the strips, or at least the portion of these surfaces nearest the teeth, are free to spread apart, and to provide resilient means adapted normally to hold the contact surfaces together. When such a 45 comb is passed through the hair, strands of hair are drawn between adjacent contact surfaces of the strips, slightly separating them against the force of the resilient means. This results in drawing the strands of hair 50 between spring-pressed surfaces and effectively removing all foreign matter from them.

While the new comb may be used for 55 cleansing hair of any sort and removing foreign matter of any sort therefrom, it is particularly adapted for removing lice and their

eggs from human hair or the hair of animals.

The utility of the invention is, however, by no means limited to the use of the comb 60 for cleansing the hair. The new comb may be worn in the hair and for this purpose it possesses advantages over the combs heretofore used in that it takes a firm grip upon the hair so that it cannot be accidentally displaced. 65

In order that the invention may clearly be understood, I will describe in detail the specific embodiment of it which is shown in the accompanying drawings, in which:— 70

Fig. 1 is a side view of a comb embodying the invention;

Fig. 2 is an end view of the comb; and

Fig. 3 is a fragmentary sectional view taken on the line 3—3 of Fig. 2 and showing 75 one of the springs and the adjustable means for retaining it in position.

The comb shown in the drawings comprises a series of tooth-forming strips 10 and a similar series of shorter tooth-forming 80 strips 11 alternating with the strips 10. The front end 12 of each strip is tapered to form a tooth of the comb. The tapered surfaces 13 of the teeth form a continuation of the contact surfaces 14 of the strips. At each 85 end of the comb is a strip 15 of the same length as the strips 10, but thicker than the other strips.

While the particular form of the means for aligning the teeth and resiliently pressing together their contact surfaces may be varied to suit particular conditions without departing from the invention, the form of such means shown in the drawing has been found satisfactory in practice. Three flexible rods 20, 21, 22 are passed through aligned holes in the strips. The rod 20 is placed near the rear edge of the comb behind the rear ends of the shorter strips 11 so that it passes only through the strips 10 100 and the end strips 15. The rods 21 and 22 pass through all the strips. Each rod is threaded at both ends for the application of nuts 23 which may be placed in recesses in the outer sides of the end strips 15. A compression spring 24 is placed about each end of each of the rods and bears at one end against one of the nuts 23 and at the other 105 against one of the edge strips 15. It is apparent that by turning the nuts 23 the tension of the springs 24 may be regulated.

Owing to the flexibility of the rods 20, 21,

22 and the space provided between the rear portions of the strips 10 by the shortness of the strips 11, the teeth 12 and the portions of the contact surfaces 14 of the strips 5 nearest to the teeth 12 may be spread apart. The tension of the springs 24 is, however, so regulated that the contact surfaces 14 of adjacent teeth are normally pressed together.

In using the new comb for cleansing the 10 hair, it is passed through the hair in the same way as in combing the hair with an ordinary comb. This results in drawing the strands of hair between the spring-pressed contact surfaces 14 and thus removing 15 all foreign matter from them.

When the new comb is worn in the hair it is placed in the hair with sufficient firmness to draw some strands of the hair between the spring-pressed contact surfaces 14 20 and the grip of these surfaces upon the hair retains the comb in proper position in the hair.

An advantage of the type of aligning means shown in the drawing is that it facilitates 25 cleaning the comb. In order to do this it is merely necessary to remove the rod 21 or the rod 22 after unscrewing one of the nuts 23. The shorter strips 11 may then be turned out of alignment with the strips 10 so 30 that all parts of the strips are accessible and the comb may be thoroughly cleansed.

Furthermore, if one of the teeth is broken, the strip having the broken tooth may be removed from the comb by taking out the 35 three rods, and the remaining strips placed together without it. The slight shortening of the comb thus caused does not seriously interfere with its utility.

If desired, the rear ends 16 of the longer 40 strips 10 may be pointed or tapered so that the rear side of the comb may be used as an ordinary coarse comb. This adds to the advantages of the comb described as it is usually desirable to comb the hair with a 45 coarse comb before cleansing it in a manner hereinbefore described.

It should be understood, however, that the 50 utility of the new comb is not limited to the particular uses described, and that the form of the comb shown in the drawing and the particular means for aligning and retaining the strips shown in the embodiment illustrated may be varied without departing from the scope of the invention.

55 What is claimed is:

1. A comb, comprising a series of separate strips arranged side by side in contact with each other and each having a tapering end forming a tooth of the comb, 60 the tapering surfaces of the sides of the teeth merging into the contacting surfaces of the sides of the strip so as to form between the teeth recesses each tapering inwardly to a point, and retaining means for 65 the strips located behind the inner ends of

said recesses to permit strands of hair to be drawn into the points of said recesses.

2. A comb formed to provide a series of teeth and an open unobstructed inwardly tapering recess between each pair of adjacent teeth, the inner portions of the opposite surfaces of adjacent teeth having the form of convex curves tangential to each other at the inner end of the recess between the teeth. 75

3. A comb, comprising a series of strips, each having a tapered end forming a tooth of the comb, each side of each strip providing a contact surface conforming to the adjacent contact surface of the succeeding strip 80 and a tapering surface being a continuation of the contact surface so as to form between the teeth recesses each tapering inwardly to a point, retaining means located behind the inner ends of said recesses for holding said strips in alignment and permitting a separation of the tapered ends of the strips and the portion of the contact surfaces of the strips nearest the tapered ends, and resilient means adapted normally to press said 85 contact surfaces into engagement.

4. A comb, comprising a series of separate strips, each having a tapering end forming a tooth of the comb, flexible means adapted to hold said strips in alignment, 90 and resilient means for pressing said strips together. 95

5. A comb, comprising a series of separate strips, each having a tapering end forming a tooth of the comb, said strips being provided with a series of aligned holes, a plurality of flexible rods extending through said holes, and yieldable means at the ends of said rods for holding said strips together. 100

6. A comb, comprising a series of strips, 105 each having a tapering end forming a tooth of the comb, a plurality of rods extending through said strips and holding them in alignment, and resilient means upon the one of said rods nearest the tapering ends of 110 said strips adapted to press said strips together.

7. A comb, comprising a series of separate strips, each having a tapering end forming a tooth of the comb, and alternate strips 115 having a portion of their rear ends cut away, a plurality of rods extending through said strips and holding them in alignment, and springs upon the one of said rods nearest the tapering portion of said strips adapted to press the strips together. 120

8. A comb, comprising a series of separate tooth-forming strips, a second series of tooth-forming strips placed alternately with said first-mentioned strips and shorter in 125 length than said first-mentioned strips, aligning means engaging the rear portions of the longer series of strips, and two aligning means engaging all the strips, one of said last-mentioned aligning means being 130

- removable to permit the shorter strips to be turned out of alignment with the longer strips to facilitate cleaning the comb.
9. A comb, comprising a series of separate strips, each having a tapering end forming a tooth of the comb, a second series of strips placed alternately with said first-mentioned strips and shorter in length than said first-mentioned strips, a rod extending 10 through the rear portions of the longer ones of said strips, two rods extending through all said strips and serving to hold them in alignment, and retaining means upon each end of each of said rods to hold said strips 15 together, the retaining means upon one end of one of the rods passing through all the strips being removable to permit removal of this rod so that the shorter strips may be turned out of alignment with the longer 20 strips to facilitate cleaning the comb.
10. A comb, comprising a series of separate tooth-forming strips, a second series of tooth-forming strips placed alternately with said first-mentioned strips and shorter in length than said first-mentioned strips, 25 means for retaining said strips with their front ends in alignment, and resilient means for pressing said strips into contact with each other, the front ends of all said strips being tapered to form closely spaced teeth 30 and the projecting rear ends of the longer of said strips being tapered to form separate teeth.

In testimony whereof I have hereunto set my hand in the presence of two subscribing 35 witnesses.

JULIUS BIDERMAN.
